GOLFER'S ACCESSORY KIT

Robert A. Bennett, 38 Falmouth Drive,
Shelton, Conn. 06484

Filed Jan. 15, 1969, Ser. No. 15,359

Term of patent 14 years

Int. Cl. D21—03

U.S. Cl. D34—5

FIG. 1

FIG. 2

FIG. 3

FIG. 4

The dominant features of the design reside in the portions shown in full lines.

I claim:

The ornamental design for a golfer's accessory kit, substantially as shown and described.
